UNITED STATES PATENT OFFICE.

G. B. PHILLIPS, OF ALBANY, NEW YORK.

HAND-WRENCH.

Specification of Letters Patent No. 17,844, dated July 21, 1857.

To all whom it may concern:

Be it known that I, GEORGE B. PHILLIPS, of the city of Albany, State of New York, have invented a new Method of Constructing 5 Hand-Wrenches; and I declare the following specification, with the drawings hereto appended as part of the same, to be a full and perfect description thereof.

Figure 1 represents the complete instrument. Fig. 2 represents the section vertically through the center of the wrench. Fig. 3 represents the jaws with their operating apparatus without the external case.

Similar letters in the different figures denote the same parts of the apparatus.

A is the case inclosing the jaws and forming the handle of the wrench. It is secured by riveting or otherwise, firmly to the lower edge, of the lower or fixed jaw, and forms 20 substantially a part of it. As it incloses the upper jaw closely for a great part of its length, in whatever position the jaw may be it is manifest that no strain upon the wrench can break it unless it be sufficient to 25 tear the casing apart; forming a resistance to stress upon the jaws not to be found in any wrenches now made of the same weight and working size.

B is the upper jaw. C the lower jaw. In 30 Fig. 2 they are shown as closed together. In Fig. 3 as slightly opened. The apparatus by which they can be opened and shut, and the extent of their opening be regulated is this: The upper jaw has teeth *a—a* cut 35 on and along its lower edge for a considerable extent of its length. In the under jaw are two rectangular blocks D and E having teeth to match the teeth of the upper jaw, and which when down in place can lie 40 wholly without the range of the teeth of the upper jaw as shown at B, Fig. 2. These blocks are kept in contact with the upper

jaw by two springs G, G, acting upon stems passing through the lower jaw under the blocks. The blocks are so fitted that when 45 one is meshing into the teeth of the upper jaw as E, Fig. 3, the teeth of the other blocks are directly opposite those of the upper jaw as D, Fig. 3.

To bring both the blocks down in their 50 sockets and thus permit the upper jaw to glide back and forth, there is a sort of saddle H, Fig. 2, consisting of two straps of metal coming down on each side of the upper jaw and resting upon pins *d, d*, in the 55 blocks. They are attached at top to a thumb piece K by pressing upon which the blocks are held down till the jaws are adjusted to their place.

From the position of the teeth of the 60 blocks in reference to those of the upper jaw it will be seen that the jaws can be regulated to a distance equal to half the space between two teeth, for if block E be withdrawn and the upper jaw be moved a half 65 space either way the teeth of D will mesh into those of the jaw. A pocket wrench of the size shown in the drawings can be made that will work at differences of $\frac{1}{2}$ of an inch.

I claim—

In combination with the jaws the arrangement described for regulating the space between the jaws, and securing them when so adjusted that is to say: by the employment of the toothed blocks operated alternately 75 upon teeth in the upper jaw, by the spring and saddle or their equivalents so as to regulate the space, to distances differing by half the space between the teeth substantially as set forth in the specification.

G. B. PHILLIPS.
